COMBINED NEEDLE, THREAD AND THIMBLE
HOLDER AND SEAM SMOOTHING

John J. Conway, 17241 Faust, Detroit, Mich. 48219

Filed Aug. 5, 1966, Ser. No. 3,349

Term of patent 14 years

(Cl. D3—19)

FIG. 1 is a side elevational view of a combined needle, thread and thimble holder and seam smoother embodying my new design;

FIG. 2 is a side elevational view taken from the right of FIG. 1;

FIG. 3 is a side elevational view taken from the left of FIG. 1;

FIG. 4 is a top plan view; and

FIG. 5 is a bottom view.

I claim:

A combined needle, thread and thimble holder and seam smoother, substantially as shown.
